US0D1008306S

(12) **United States Design Patent** (10) **Patent No.:** **US D1,008,306 S**
Lynne et al. (45) **Date of Patent:** **** Dec. 19, 2023**

(54) **DISPLAY SCREEN OR PORTION THEREOF WITH GRAPHICAL USER INTERFACE FOR MEDIA PLAYBACK CONTROL**

(71) Applicant: **Sonos, Inc.**, Santa Barbara, CA (US)

(72) Inventors: **Brandon Lynne**, Santa Barbara, CA (US); **Ryan Kitson**, Santa Barbara, CA (US)

(73) Assignee: **Sonos, Inc.**, Santa Barbara, CA (US)

(**) Term: **15 Years**

(21) Appl. No.: **29/869,802**

(22) Filed: **Jan. 9, 2023**

Related U.S. Application Data

(63) Continuation of application No. 29/866,297, filed on Sep. 7, 2022, now Pat. No. Des. 975,126, which is a continuation of application No. 29/672,604, filed on Dec. 6, 2018, now Pat. No. Des. 963,685, which is a continuation-in-part of application No. 16/212,437, filed on Dec. 6, 2018, now abandoned.

CLAIM

The ornamental design for a display screen or portion thereof with graphical user interface for media playback control, as shown and described.

DESCRIPTION

FIG. 1 is a front elevational view of a first embodiment of a display screen or portion thereof with graphical user interface for media playback control; and,

FIG. 2 is a front elevational view of a second embodiment of a display screen or portion thereof with graphical user interface for media playback control.

The dot-dash broken lines illustrate a display screen or portion thereof and form no part of the claimed design. The dashed broken lines illustrate portions of the graphical user interface and form no part of the claimed design.

1 Claim, 2 Drawing Sheets
